UNITED STATES PATENT OFFICE.

REUBEN B. BENJAMIN, OF CHICAGO, ILLINOIS, ASSIGNOR TO BENJAMIN ELECTRIC MANUFACTURING COMPANY, OF CHICAGO, ILLINOIS, A CORPORATION OF ILLINOIS.

SHADE-HOLDER.

1,247,493.

Specification of Letters Patent. Patented Nov. 20, 1917.

Application filed April 23, 1915. Serial No. 23,368.

To all whom it may concern:

Be it known that I, REUBEN B. BENJAMIN, a citizen of the United States, residing at Chicago, in the county of Cook and State 5 of Illinois, have invented new and useful Improvements in Shade-Holders, of which the following is a full, clear, concise, and exact description, reference being had to the accompanying drawing, forming a part 10 of this specification.

My invention relates to shade holders.

Among the objects of my invention is to provide a shade holder which shall be simple in construction and which may be easily attached to the shade and to the supporting device and which will hold the shade securely on the supporting device.

Further objects of my invention will appear from the detailed description to follow taken in connection with the appended claims.

Referring to the drawings, in which I have illustrated several embodiments of my invention—

25 Figure 1 is a view partly in section showing a form of my improved holder for use with a shade having a beaded sheet metal top;

30 Fig. 2 is a plan view of the shade holder in Fig. 1, showing in dotted lines the blank from which the holder is formed;

35 Fig. 3 is a perspective view of part of the holder showing the tongues for engaging the bead on the lamp socket;

35 Fig. 4 is a view partly in section showing a form of my holder for use with a glass shade having a downward and outward flaring neck portion;

40 Fig. 5 is a plan view of the holder shown in Fig. 4, showing, in dotted lines, the blank from which the holder is formed;

45 Fig. 6 is a perspective view of part of the holder showing the fingers for engaging the bead of the lamp socket, and showing a projection which snaps over the upper edge of the shade;

50 Fig. 7 is a view of a form of my device for use with an all metal shade holder having an inside shoulder;

55 Fig. 8 is a plan view of the holder of Fig. 7 showing in dotted lines the blank from which it is formed;

55 Fig. 9 is a perspective view of part of the holder showing the tongues for engaging

the bead of the socket, and showing a projection which snaps over the upper edge 55 of the shade when the holder is in place;

Fig. 10 is a view partly in section of a modification in which spring locking means are provided for holding the spring tongues 60 in engagement with the lamp socket above the bead;

Fig. 11 is a plan view of the holder of Fig. 10, showing the blank from which it is formed, in dotted lines; and 65

Fig. 12 is a perspective view of part of the holder showing the socket engaging tongues and the projection struck up from one of the tongues for engaging the coil spring to hold it against the socket engaging 70 portion of the spring tongue.

Referring now to the drawing in detail and first to the modification of Figs. 1, 2 and 3, I have shown the improved holder in combination with a lamp socket 15 having 75 an annular bead 16 for engagement with the shade holder, and also in combination with a lamp shade 17 having a sheet metal top 18 which is flanged over as shown at 19, and secured to the bowl portion, and having 80 an inwardly extending annular bead 20, which, with the usual construction of holder, provides a recess for the retaining screws of the shade holder, and having an inwardly extending flange 21 which forms a 85 finish for the upper part of the shade. The shade holder comprises an annular shoulder portion 22 for engagement with the inwardly extending flange 21 of the shade, and downward and outward extending 90 spring tongues 23 which engage within the annular recess between the inwardly extending bead 20 and the inwardly extending flange 21 when the holder is secured to the shade. The holder also comprises inwardly 95 extending tongues 24 for engagement with the lower edge of the bead 16 of the socket, and hook shaped spring tongues 25 for engagement with the upper edge of the bead 16. The spring tongues 25 may be provided 100 with openings 26 to lessen the stiffness of the springs.

The form of the blank from which the holder is struck up is shown in dotted lines at 27 in Fig. 2.

105 The holder is secured to the shade by slipping it into position from the inside of the shade, the spring tongues 23 being bent in-

wardly as they pass the restricted throat formed by the bead 20 of the shade, and springing out again into the position shown in Fig. 1 after they pass the bead 20. The 5 holder is secured to the lamp socket by simply slipping it in place over the end of the socket, the spring fingers 25 yielding outward to permit this and springing in again over the upper edge of the bead. The 10 fingers 24 engage the lower edge of the bead 16 to limit the distance to which the holder can be moved.

It will be seen that owing to the downward and inward direction in which the 15 ends of the spring fingers 25 extend the holder can be easily slipped onto the socket, but cannot easily be removed therefrom by jarring, as a downward pull on the shade holder would tend to cause the ends of the 20 spring fingers 25 to bite into the lamp socket and bead 16 rather than to slip over it.

In the modification of Fig. 4 I have shown a holder adapted for use with a glass shade 25 30 having a downward and outward flaring neck portion 31 and a bead 32 at the top beneath which the screws of the ordinary shade holder may engage to secure the shade on the holder. For this form of shade my 30 improved holder is provided with a downward and outward flaring portion 33 shaped to conform to the inner surface of the neck portion 31 of the shade, and is provided with inwardly extending tongues 34 for engagement with the lower edge of the bead 16. 35 Spring fingers 36 are struck up from the spring tongues 35 to secure the holder in position on the shade. The shape of the blank from which the holder is formed is indicated in dotted lines at 37 (Fig. 5).

40 In this modification in securing the holder to the shade the holder is inserted within the shade from the lower side, the spring fingers 36 being pressed inward by engagement with the inner surface of the neck portion 31 as the holder is being moved into position, and springing out again after they have passed the contracted portion of the neck to secure the holder in place, as shown in Fig. 4. The flaring portion 33 45 snugly engages the inner surface of the neck portion 31 and prevents the shade from slipping down off from the holder. The engagement of the retaining tongues 34 and 35, in this modification, with the bead 16 50 on the socket is substantially the same as the engagement of the fingers 24 and 25 in Fig. 1.

55 In the modification of Figs. 7, 8 and 9 I have shown a holder for use with a sheet metal shade 40 having a cylindrical portion

41 and an inwardly extending flange 42 forming a shoulder for engagement with the outwardly extending flange 43 of the shade holding device. The shade holder of this modification is provided with tongues 70 44 and 45 which engage with the bead 16 of the lamp socket in substantially the same manner as the tongues 34 and 35 of the modification of Figs. 4, 5 and 6, spring fingers 46 being struck up from the spring tongues 45 for engagement with the upper surface of the flange 42 of the shade. The shape of the blank from which the holder is formed is shown in dotted lines at 47 in Fig. 8. In securing this holder to the shade 80 the holder is inserted into the shade from below, the spring fingers 46 being forced inwardly until they have passed the flange 42 when they snap up to secure the shade and holder in position.

85 In the modification of Figs. 10, 11 and 12 I have shown a device for use with a glass shade 50 having a neck portion 51 and an outwardly extending bead 52 beneath which 90 engage the retaining screws 53 which are threaded through lugs 54 extending downward from a flange or skirt portion 55 of the holder. This holder also is provided with socket engaging fingers 56 and 57 which engage the bead 16 of the socket in substantially the same manner as the fingers 45 and 46 of the modification of Figs. 7, 8 and 9. Projections 58 are struck up from the spring fingers 56 for engagement with the upper coil of the coil spring 59 which is held in place between the inwardly extending fingers 57 and the downward and inward extending portion 60 of the spring fingers 56. The tension in the spring 59 is such as to tend to force the upper coil of the spring upwardly and to wedge it between the projections 58 and the downward and inward extending portions 60 of the spring fingers 56. In securing the holder of this modification to the socket the spring 59 must be compressed so that the upper coil is not wedged between the projection 58 and the portions 60 in order that the portions 60 may spring inwardly as the holder is slipped outward over the bead 16. After the portions 60 are above the bead 16 the spring 59 may be released to permit the upper coil to wedge in between the portion 60 and the projections 58 to prevent a downward pull on the holder from causing the portions 60 to spring outward and slip off from the bead 16.

110 In all of the modifications it will be noted that the entire device is formed from a single piece of sheet material, and that all of the 115 holders are provided with hook shaped spring tongues or fingers, the ends of which engage a bead on the socket or supporting device.

120 Having thus described my invention what 130

I claim as new and desire to secure by Letters Patent is:—

1. A shade supporting device for connecting a shade to a beaded lamp socket comprising shade engaging means and bead engaging means, said bead engaging means comprising a plurality of spring tongues each having a portion extending upwardly from the shade engaging means, and a portion extending downward and inward for engaging the upper portion of the bead and a plurality of tongues staggered with respect to said spring tongues for engaging the lower portion of the bead, both sets of tongues being formed from a single piece of sheet material.

2. A shade supporting device for connecting a shade to a beaded lamp socket comprising shade engaging means and bead engaging means, said bead engaging means comprising a plurality of spring tongues extending downward and inward for engaging the upper portion of the bead, said bead engaging means comprising also inwardly extending tongues, staggered with respect to said spring tongues for engaging the lower portion of the bead, both sets of tongues being formed from a single piece of sheet material.

3. The combination with a lamp socket having a bead, of a shade supporting device comprising a plurality of spring tongues, each having a portion extending upward from the shade engaging means, and a portion extending downward and inward for

engaging the upper portion of the bead and a plurality of tongues staggered with respect to said spring tongues for engaging the lower portion of the bead, both sets of tongues being formed from a single piece of sheet material.

4. The combination with a lamp socket having a bead, of a shade supporting device comprising shade engaging means and bead engaging means, said bead engaging means comprising a plurality of spring tongues extending downward and inward for engaging the upper portion of the bead and a plurality of tongues staggered with respect to said spring tongues for engaging the lower portion of the bead, both sets of tongues being formed from a single piece of sheet material.

5. The combination with a lamp socket having a bead and a lamp shade, of a shade holding device formed of a single piece of sheet metal comprising an annular portion, and a plurality of spring tongues integral therewith for engagement with the upper portion of said bead and a plurality of inwardly extending tongues integral therewith staggered with respect to said spring tongues for engaging the lower portion of the bead.

In witness whereof, I have hereunto subscribed my name.

REUBEN B. BENJAMIN.
